UNITED STATES PATENT OFFICE.

OTTO KRAUS, OF NEW YORK, N. Y.

GARMENT-SUPPORTER.

SPECIFICATION forming part of Letters Patent No. 730,029, dated June 2, 1903.

Application filed February 11, 1903. Serial No. 142,857. (No model.)

To all whom it may concern:

Be it known that I, OTTO KRAUS, a citizen of the United States, and a resident of New York, in the county of New York and State of New York, have invented certain new and useful Improvements in Garment-Supporters, of which the following is a specification.

This invention has reference to garment-supporters, and as disclosed herein is more particularly designed for service as a hose-supporter.

One of the prominent objects of the invention is to insure the positive engagement of the clamping members, but permit the self-adjustment of the latter for readily accommodating themselves to firmly hold different thicknesses of fabric without a proportionate increase or decrease of pressure on the engaged portion of the same.

With the above and other purposes in view the invention consists of a novel construction of garment-supporter of that type wherein the clamped and clamping members are so constituted that the engaging provision of one of said members is of greater dimension than that of the other member, so that mutual engagement of these parts requires a relative change in position of one of the same before either engagement or disengagement can be effected.

Another important feature involved in the invention is the novel arrangement providing for the increased downward tension or pull on the material of the garment, resulting in its being more firmly gripped in the supporter.

The novel construction also provides increased bearing-surface, against which the fabric is held, whereby the liability of the fabric to become torn or injured is reduced.

There are other novel details and combinations of parts connected with the invention, which are fully explained in the subsequent extended description.

In the accompanying drawings, forming part of this specification, Figure 1 is a perspective view of a garment-supporter, showing one form of my invention, said supporter being represented in an open position. Figs. 2 and 3 are sectional detail views, on an enlarged scale, showing the members partly and completely engaged, the section being taken

in the plane indicated by the broken line 23, Fig. 1, the garment fabric being represented and the suspending-webbing omitted. Fig. 4 is a detail section on the line 44, Fig. 2, showing the side flanges, which do not appear in Fig. 1. Fig. 5 is a perspective view of the keeper forming part of the clamped member. Figs. 6 and 7 are perspective views of the two members, presenting another form of my invention. Fig. 8 is a detail sectional view taken in the plane indicated by the broken line 88, Fig. 7. Figs. 9 and 10 are perspective and side views, respectively, of a still further form of the invention. Fig. 11 is a face view, and Fig. 12 a central vertical section, respectively, exemplifying another embodiment of the supporter. Fig. 13 is a view somewhat similar to Fig. 11, but showing a slight modification of the construction disclosed in that figure. Fig. 14 is a face view illustrating a clamping member and part of the clamped member of another form of the supporter, this view more particularly suggesting the artistic possibilities of the device. Figs. 15 and 16 are face views illustrating additional modifications of the supporter.

Similar reference characters are employed to designate corresponding parts throughout the several figures of the drawings where they occur.

Referring now more particularly to Figs. 1 to 5, inclusive, the suspending-webbing A is shown as having the upper transverse fold stitched to present the depending bight A', the webbing then continuing down back of and upwardly around, threaded through, and secured to suspend the slotted plate B of the member to be clamped. The member to be clamped, or, as it will hereinafter, for brevity, be frequently referred to as the "clamped" member, comprises a section of suitable yielding material, preferably rubber, integrally embodying the inner part C and top or larger portion C', the relative increase in the latter being at its upper and lower ends to present overhanging flanges c c'. Lateral flanges c² may also be at the sides, as indicated in Fig. 4. Centrally in the upper or outer face of the portion C' is a shallow longitudinal channel c³, which also continues through the flanges c c' and down

the upper and lower ends of the body C. Snugly within the channel thus formed is a thin metallic strap or keeper D, generally conforming to the longitudinal configuration 5 of the yielding section, the ends of said keeper being reduced to form short tongues d, adapted to be passed through appropriately-located openings therefor in the central portion of the plate B and clenched against the 10 same to positively connect the yielding section thereto. Shoulders d' at the intersection of the tongues with the rest of the keeper constitute stops, between which and the turned portions of the tongues the plate B is 15 clamped to securely attach the keeper in position. It will be observed, as indicated in Figs. 2 and 3, that the flange c' is somewhat more extended than is the flange c. The clamping member is shown as being of wire 20 and consists of the downwardly-contracting shank F, having the inturned extensions at its upper end constituting a bar e, bearing in the bight A' for pivotally suspending the member. At its lower contracted end the 25 shank E merges in the rectangular open frame or head E', embodying the closed lower cross-bar e' and practically closed upper bar e². The distance between the inner sides of the bars e' e² of the head E' is considerably 30 less than that between the outer ends of the upper and lower flanges c c' of the yielding section carried by the clamped member. Consequently, in order to accomplish the engagement of the head E' beneath the flanged 35 top of the yielding section it will be necessary to hold the head at such angle that its bar e' can be moved beneath the lower flange c', as indicated in Fig. 2, after which the head can be moved upward to such extent as will permit its bar e² to be passed 40 beneath the flange c, whereupon a slight downward movement of the head will bring both bars e' e² in such position as will prevent the disengagement of the head from the yielding 45 section, as shown in Fig. 2. The relative widths of the part C of the yielding section and the head E' are such that considerable clearance is afforded between the sides of said part and the sides e³ of the head. This not 50 only conduces to the convenient manipulation of the members during the engaging and disengaging operations, but affords room for the fabric between the section sides and those of the head. Assuming the parts to be in the 55 position illustrated in Fig. 1, the fabric of the garment is drawn well on the top of the yielding section, and while thus held the clamping member is manipulated so that its head assumes an angular position with respect to the 60 plate B, such position being possible by reason of the free character of the bight A'. By reason of such manipulation the bars e' e² of the head can then be successively introduced beneath the flanges c' c, as previously described, thus causing the garment fabric F to be engaged against the face of the top and

around and beneath the flanges c c' of the same. Manifestly the fabric F is maintained in such clamped relation by reason of the bars e' e² being, on account of the comparatively 70 restricted distance between the same, ordinarily prevented from leaving their position beneath the flanges. The clinging character of the surface of the top and flanges of the yielding section also largely contributes to 75 augment the engagement. Moreover, downward tension exerted on the fabric, inevitably experienced during use, operates while downwardly moving the bar e' to correspondingly influence the bar e², so that the greater the 80 tension the more positively will said latter bar bear against the end surfaces of the body C and serve to not only more firmly grip the fabric against the same, but also cause said fabric to more intimately adhere to the frictional surfaces presented on the top and by 85 the upper flange c. The engagement of the bar e² beneath the flange c is insured and accelerated by a spring d², integrally formed with the lower part of the keeper, as more 90 clearly illustrated in Fig. 5. This tongue can be formed by slitting the metal of the keeper beneath the flange c' and then bending the tongue so formed that as the bar e' is moved up beneath the flange c' to permit the bar e² 95 to clear the flange c said spring will be compressed by the bar e', and when the bar e² arrives opposite the space beneath its flange the spring will react to downwardly move the lower bar, and thereby drag the upper bar 100 into a position beneath its flange. In most cases the downward tension of the garment will accomplish this result. The relation and play of the bars e' e² with respect to the yielding section are such that fabrics of different thicknesses can be securely clamped 105 without any proportionate increase or decrease in the clamping - pressure resulting. It will be noted that the bar e² is slightly curved in a direction away from the contiguous 110 end of the yielding section. By this arrangement the downward tension exerted on the fabric will cause said curved bar to move in relation to the section end and assume a centered position with respect to said 115 section. This is particularly efficient where the engaging flanges of the yielding section are transversely disposed, as will be described. In practice the width of the head will afford such ample clearance between its 120 sides and those of the clamped member as to accommodate the greatest thickness of hose without undue pressure, and inasmuch as there will also be a clearance between the top and bottom bars of the head and the 125 part C' of the clamped section when in position there will be no undue pressure exerted by either of said top and bottom bars, thus permitting the greatest scope for engagement of garment fabrics of different thicknesses 130 without involving a wedging or jamming action. The distance between the flanges c c'

and the plate B is also such as to avoid jamming of the fabric between said flanges and the plate. It will be observed that the ends of the flanges c c' , as well as the fabric-engaging surfaces of the upper and lower bars of the head, are liberally rounded, so that the turns of the fabric around said flanges and bars are such as to avoid sharp or abrupt bends in the fabric when engaged.

In the construction disclosed in Figs. 6 and 7 some of the conditions of the previously-described supporter are reversed. B' refers to the plate of the clamped member, laterally extended at both ends to provide for the slots b adapted for the webbing. The body of the plate is slotted and turned over to present the overhanging upper and lower flanges B² B³, the latter of which is considerably more extended than the former. The clamping member E² has the slotted enlargement e^4 at its upper end for attachment of the webbing. The plate contains a liberal opening e^5 , contiguously extending from the slotted enlargement to a head E³, presented by the lower portion of the plate. Said head is provided with yielding gripping-surfaces formed by cylindrical sections e^6 e^7 , applied to the upper and lower transverse edges of the head, such sections having transverse horizontal grooves extending partly through the same for the reception of the edge portion of the head, as indicated most clearly in Fig. 8. The metal of the plate E² contiguous to the ends of the section e^6 is recessed, so that the section ends 35 can be sprung therein so as to retain said section in position upon the upper transverse edge. The lower section e^7 is correspondingly retained in position on the lower transverse edge by means of ears e^8 at the lower end of the plate E² and bent for a slight distance around the section ends. It will be understood that the width of the sections e^6 e^7 between the end-retaining provision is in excess of that of the overhanging flanges B² B³, so that when the garment fabric is drawn across the front of the plate B' it can be secured by manipulating the clamping member E², so that the lower end of its head can be introduced within the deeper slot presented by the lower flange B³ and thereafter the upper portion of said head moved down and within the slot presented by the upper flange B².

From the description immediately above it will be seen that practically all the conditions involved in the device first described are also present in the construction disclosed in Figs. 6 to 8, inclusive.

In Figs. 9 and 10 I have shown an arrangement somewhat similar to that illustrated in Fig. 1, but having the flanges c^5 c^6 of the yielding section, which serve to maintain the two members engaged, laterally disposed instead of longitudinally, as in the first instance. In this arrangement embodying the laterally-disposed flanges the engagement of the head E⁴ with the yielding section is effected by in-

clining said head toward one side, so as to permit one of its side bars e^9 to pass beneath one of the lateral flanges and move beneath the same, to enable the other side bar to inwardly clear and move beneath the other lateral flange. The gripping of the fabric F is effected between the upper edge e^{10} of the opening in the head and the contiguous end of the yielding section, the lower portion of the fabric passing beneath the lower bar e^{11} , so as to maintain said fabric not only in frictional engagement with the top of the yielding section, but also coöperate through the downward tension on the fabric to cause the upper edge e^{10} to more firmly clamp said fabric against the contiguous end of the yielding section. e^{12} refers to the upper enlarged slotted portion of the head for its suspension, while upper and lower enlarged slotted portions b^1 b^2 provide for the connection of the webbing with clamped member F⁴.

Figs. 11 and 12 illustrate an arrangement of the device wherein the plate B⁵ has the upper turns b^3 clamping the ends of the suspending-cords A². The body of the plate a short distance below the turns is slotted to form ears which are outwardly bent toward each other to constitute a loop b^4 , through which plays the shank E⁵ of the wire-clamping member formed by the vertical closely-parallel wire extensions, the upper terminal portions b^5 of which are oppositely bent horizontally to prevent the downward withdrawal of the shank from the loop. The lower part of the clamping member is shaped to constitute the head E⁶ of open character, but having the lateral loops e^{13} for serving as finger-pieces in transversely tilting the head to effect its engagement with and disengagement from the transversely-disposed flanges c^7 c^8 of the yielding section B⁶, secured on the lower part of the plate B⁵. Instead of attaching the yielding section by a separate metallic keeper I have in this instance shown tongues b^6 as bent up from the plate B⁵ and turned over within the channel b^7 in the yielding section. Palpably the fabric passes over the head and beneath the upper and lower end bars e^{14} e^{15} of the head, downward tension exerted by the fabric on the latter operating to cause the bar e^{14} to more positively grip the fabric against the contiguous end of the yielding section. The liberal character of the loop b^4 permits the movable member to swing to one side or the other and to be raised or lowered to any desired extent, the play of the shank E⁵ within said loop providing for these several movements.

A device similar in some particulars is illustrated in Fig. 13, the plate B⁷ of the inner member having upper and lower slotted enlargements b^8 b^9 at its ends for the connection of a suspending webbing A³. The head E⁷ of the wire-clamping member is successively engaged with and disengaged from the transversely-disposed flanges c^9 c^{10} of the yielding

section, the head being provided with a lower depending operating-loop e^{16} instead of side loops, as in Fig. 11. A corresponding arrangement of wire shank E^8 , having oppositely-bent upper ends e^{17} and confining-loop b^{10} , permits the various movements of the movable member while insuring its permanent attachment to the other member.

The movable member, which will generally

- 10 be that exposed at the outer side of the garment when clamped, may be made to partake of various artistic configurations to impart an attractive and finished effect to the supporter. For instance, as illustrated in Fig. 14, the shank E^9 of said member may have the triangular effect indicated and the head E^{10} shaped to present somewhat the shape of a horseshoe in outline. The bizarre or ornate effect will be heightened by making the yielding section B^8 vertically long and narrow, the supporting part B^9 thereof (dotted lines, Fig. 14) being so located to provide the upper shorter and lower longer engaging flanges $c^{11} c^{12}$.

- 25 In Fig. 15 I have represented an arrangement wherein the plate B^{10} has the enlarged upper and lower ends $b^{11} b^{12}$ for the attachment of the suspending webbing A^4 in an obvious manner. The flanges $c^{13} c^{14}$ of the yielding section are at the upper and lower ends thereof to be engaged by the head E^{11} , the shank E^{12} of which presents a transverse loop E^{13} at its upper end in sliding engagement with the webbing. Fig. 16 discloses 30 substantially the same arrangement as applied to a cord-suspended supporter, the upper and lower flanges $c^{15} c^{16}$ of the yielding section, carried by the plate B^{11} , being engaged by the head E^{14} , the shank E^{15} of which has an upper loop E^{16} slidably embracing the cords A^5 .

One of the important features connected with garment-supporters embodying my invention resides in the provision whereby comparatively large or extended bearing-surfaces are provided for the fabric, particularly at the gripping portions of the device.

The novel device embodying my invention is not only simple, but is convenient of operation and is highly efficient in use. It can be 50 embodied in comparatively few parts, which can be produced and assembled at small expense.

In those constructions where the flanges of the clamped member are laterally disposed the downward tension of the fabric operates 55 to hold the head in a central position with respect to said section, and thereby prevent the disengagement of the head sides from the flanges.

60 It will be noted that in the embodiments of the invention illustrated in the different figures of the drawings the relatively remote and laterally-disposed side edges presented by the flanges, whether the latter be transverse or vertical, are of such free character that when the head is brought into coactive

relation and engages the fabric the latter is laterally disposed in a simple and even manner at both sides of the head at the external portions of said head sides.

I do not wish to be understood as limiting myself to the precise constructions shown and described, but reserve the right to all such modifications as may be fairly within the scope of my invention.

Having now described my invention, what I claim as new, and desire to secure by Letters Patent, is—

1. A garment-supporter comprising a suspended member with juxtaposed flanges having relatively remote and laterally-located free outer edges, and a second member including fabric-engaging portions adapted to be successively engaged with and simultaneously lie beneath said flanges.

2. A garment-supporter comprising a suspended member embodying a plate with juxtaposed flanges having relatively remote and laterally-located free outer edges, and a second member including fabric-engaging portions adapted to be successively engaged with and simultaneously lie beneath said flanges, one of said members having a yielding fabric-engaging surface.

3. In a garment-supporter, a member comprising a horizontally-projecting section with juxtaposed flanges having relatively remote and laterally-located free outer edges, and a second member adapted to be brought into shiftable coactive relation with the section for successively engaging the fabric at distinct points at opposite sides of the section and for simultaneously lying beneath said flanges.

4. In a garment-supporter, a member comprising a plate and a section projecting horizontally therefrom, and provided with juxtaposed flanges forming with said plate, recesses, the flanges having relatively remote and laterally-located free outer edges, and a second member adapted to be brought into shiftable relation with the section for successively engaging the fabric at distinct points at opposite sides of the section.

5. In a garment-supporter, a member comprising upper and lower transverse flanges with relatively remote and laterally-located free outer edges, a second member adapted to swing outwardly and having portions for successively entering and simultaneously lying beneath said flanges, and provision for cooperatively supporting said members.

6. In a garment-supporter, a member comprising relatively divergent flanges with laterally-located free outer edges, and a second member having portions for successively entering and simultaneously lying beneath said flanges.

7. A garment-supporter comprising a member having juxtaposed flanges providing recesses of relatively varying sizes, a second member having fabric-engaging portions

adapted to successively enter and simultaneously lie within said recesses, and provision for coöperatively suspending said members for the purpose specified.

5. 8. A garment-supporter comprising a member having juxtaposed flanges providing recesses of relatively varying size, a second member having fabric-engaging portions adapted to successively enter and simultaneously lie within said recesses, a yielding fabric-engaging surface embodied in said supporter, and provision for coöperatively supporting said members for the purpose specified.

15. 9. In a garment-supporter, a member comprising a supporting-plate, a recessed engaging section secured to and projecting from the plate, a second member comprising an open head varying in size in one direction relative to said section and adapted to be brought into coactive relation with the section for successively engaging the fabric at distinct points at opposite sides of the section, and provision for coöperatively supporting said members for the purpose specified.

20. 10. In a garment-supporter, a member comprising a supporting-plate, a section secured to and projecting from said plate and having oppositely-located overhanging flanges, a second member comprising an open head presenting engaging portions, said second member adapted to be brought into coactive fabric-engaging relation with the section by the successive engagement of the portions with the flanges, and provision for coöperatively supporting said members for the purpose specified.

25. 11. In a garment-supporter, a member comprising a section having oppositely-located overhanging flanges, a second member comprising an open head presenting engaging portions, said second member adapted to be brought into coactive fabric-engaging relation with the section by the successive engagement of the portions with the flanges, and a spring for moving the portion last engaged more completely beneath its flange.

30. 12. In a garment-supporter, a member comprising a supporting-plate, a section secured to and projecting from said plate and having overhanging flanges of varying size, a second member comprising an open head presenting upper and lower fabric-engaging portions and adapted to be successively engaged with the flanges, and provision for coöperatively supporting said members for the purpose specified.

35. 13. In a garment-supporter, a member comprising a supporting-plate, a section secured to and projecting from the plate and having overhanging flanges of varying size and rounded in the direction of the plate, a second member comprising an open head presenting upper and lower fabric-engaging portions and adapted to be successively engaged with the

flanges, one of said members having a yielding fabric-engaging surface, and provision for coöperatively supporting said members for the purpose specified.

40. 14. In a garment-supporter, suspending provision, a plate supported thereby, a section secured to and projecting from the plate and having overhanging flanges extending in opposite directions, and a head pivotally suspended to swing outwardly from the plate and adapted to be successively engaged with said flanges, said head embodying upper and lower fabric-engaging bars, the upper bar being arched or outwardly curved relative to the contiguous portion of the section.

45. 15. In a garment-supporter, a member comprising a yielding section having oppositely-located engaging flanges and a second member adapted to be successively engaged with said flanges and embodying upper and lower fabric-engaging bars.

50. 16. In a garment-supporter, a suspending provision, a plate supported thereby, a section secured to and projecting from the plate, said section having a yielding fabric-engaging portion at its outer end and provided with overhanging flanges extending in opposite directions, and a head pivotally suspended to swing outwardly from the plate and adapted to be successively engaged with said flanges, said head embodying upper and lower fabric-engaging bars.

55. 17. In a garment-supporter, a member comprising a supporting-plate, a head having a yielding fabric-engaging surface and presenting overhanging flanges, a keeper carried by the plate and supporting the head, and a second member adapted to be successively engaged with said flanges and embodying upper and lower fabric-engaging bars.

60. 18. In a garment-supporter, a member comprising a supporting-plate, a head having a yielding fabric-engaging surface and presenting overhanging flanges, a keeper carried by the plate, embracing said head and bent around opposite ends thereof, and a second member adapted to be successively engaged with said flanges and embodying upper and lower fabric-engaging bars.

65. 19. In a garment-supporter, a member comprising a supporting-plate, a head provided with a channel and having a yielding fabric-engaging surface and presenting overhanging flanges, a keeper carried by the plate, lying within the channel and bent around the opposite ends of the channeled head, and a second member adapted to be successively engaged with said flanges and embodying upper and lower fabric-engaging bars.

70. 20. In a garment-supporter, a member comprising a yielding section presenting the flanged head and body, and a second member adapted to be successively engaged with said flanges and embodying upper and lower fabric-engaging bars.

75. 21. In a garment-supporter, a member com-

prising a plate, a flanged head and body the latter having a channel, a keeper carried by said body, embracing said head, and lying within the channel at the upper side of the 5 body, and a second member adapted to be successively engaged with said flanges and embodying upper and lower fabric-engaging bars.

Signed at New York, in the county of New York and State of New York, this 7th day of ¹⁰ February, A. D. 1903.

OTTO KRAUS.
